Harold C. Johnston, Dayton, Ohio

Application May 15, 1957, Serial No. 46,181

Term of patent 14 years

(Cl. D37—1)

FIG. 1

FIG. 2

FIG. 3

FIG. 4

FIG. 5

Figure 1 is a side elevational view of a grinding wheel dresser, embodying my new design.

Figure 2 is an enlarged top plan view of the handle element.

Figure 3 is a bottom plan view of the handle element.

Figure 4 is an end elevational view, as viewed from the right of Figure 2.

Figure 5 is an enlarged cross sectional view, taken substantially on the line 5—5 of Figure 1.

The dominant feature of my design resides in the portion shown in full lines.

I claim:

The ornamental design for a grinding wheel dresser, as shown and described.
